UNITED STATES PATENT OFFICE.

LEOPOLD HERRMAN, OF NEW YORK, N. Y.

HANDLE-FASTENER.

SPECIFICATION forming part of Letters Patent No. 691,377, dated January 21, 1902.

Application filed October 3, 1901. Serial No. 77,383. (No model.)

To all whom it may concern:

Be it known that I, LEOPOLD HERRMAN, a citizen of the United States, residing in the borough of Manhattan, city, county, and State 5 of New York, have invented certain new and useful Improvements in Handle-Fasteners, of which the following is a specification.

The object of my invention is to provide improved means for fastening a handle to 10 articles of various kinds—for instance, to brushes, carpet-sweepers, tools, baby-carriages, and so on.

The description following hereinafter discloses, in connection with the accompanying 15 drawings, what I consider to be a representative example of my invention. It will be understood, however, that in various respects the construction may be altered and that the novel features of my invention are those which 20 are pointed out in the claim.

In the drawings just referred to, Figure 1 is a plan of my improved handle-fastener. Fig. 2 is a sectional elevation thereof on line 2 2 of Fig. 1. Figs. 3 and 4 are cross-sections 25 on line 3 3 of Fig. 2, and Fig. 5 is a partial cross-section on line 5 5 of Fig. 3.

A represents the article to which the handle is attached. This may be, for instance, the back of a brush or the casing of a carpet-sweeper. I designate it by the generic term 30 of the "body." This body is formed with a recess or socket A', which is curved to receive the handle-holder B, mounted to turn, as will be described presently. This handle-holder 35 may, as shown, be of approximate ball shape. The holder is formed at diametrically opposite points with apertures or recesses b, which are in alinement with each other. When the material out of which the holder B is made 40 is not sufficiently hard, I may provide these sockets with metal linings C. Into these sockets project pins D, the outer ends of which are formed with flat enlargements or eyes D', through the apertures of which are passed 45 screws E or equivalent securing devices, which extend into the body A. It will be observed that these securing devices bind the flat portions D' of the pivot-pins D directly against the outer surface of the body A. It will be 50 understood that the pins D form pivots for the holder B, which is thus adapted to rock and even to turn completely around in a trans-

verse or vertical plane. The holder B is formed preferably in the plane in which it rocks with a socket for the reception of the 55 end of the handle F. This socket extends entirely through the holder B and has, as shown, a screw-threaded portion B', which extends from one end of the socket to an enlarged portion B' at the other end of the 60 socket. This enlarged portion is of such diameter as to receive the main portion or body of the handle F, as shown in Figs. 2 and 3, while the screw-threaded reduced end F' of the handle fits the screw-threaded portion B' of the socket. The peculiar fastening device for the pivot-pins D holds them securely in place, as their flattened ends D' are clamped tightly against the body A. The handle F has its end portion F' made of such 65 a length that when the handle is inserted in the position shown in Figs. 2 and 3 its end may abut against the wall of the socket A', and of course if the handle is screwed in until a binding contact is effected between its 70 end and the wall of said socket the handle will be kept in a fixed relation to the body A. By slightly unscrewing the handle it can be 75 turned with the holder B on the pivots D and brought to any position, as exemplified by the inclined dotted lines of Figs. 3 and 4. Preferably that end of the holder B which is opposite the socket portion B' is flattened, so that the rounded end of the handle may more readily project from the holder. This flattened portion may serve a further useful purpose. 85

When adjusted as hereinbefore described, the handle will be rigidly connected with the body A when the article, such as a brush, of 90 which the said body forms a part is in use.

In some cases it may be found convenient to use the article while the handle is loosely connected therewith, so that it is capable of a swinging movement, as when the handle is 95 attached to a sweeper. Of course this result might be obtained by slightly unscrewing the handle from the position shown in Fig. 3. This, however, would be objectionable for the reason that the handle would be loose in the 100 holder B, and to obviate this the handle is removed entirely from the holder, and the latter is reversed, so that the wide socket portion B' will be within the socket A' of the body,

and when the holder is in this reversed position the handle F is screwed in from the screw-threaded portion B' of the socket. The shoulder which is formed at the junction of the body of the handle with the end portion F' will then abut against the flat portion or shoulder B³ of the holder B. Inasmuch as this flat portion or shoulder is farther away from the center or pivot line than the shoulder which is formed at the junction of the two socket portions B' and B², it will be obvious that in this position (shown in Fig. 4) the free end of the handle portion F' will not engage the wall of the socket A'. Thus while the handle will be screwed tight to the holder B the latter will be practically free to turn on the pivots D.

Having described my invention, what I claim, and desire to secure by Letters Patent, is—

The combination of the body, pivots provided with flat portions engaging the body, securing devices for pressing said flat portions against the body, a holder provided with sockets for engaging said pivots and with a transversely-disposed through-aperture screw-threaded, at least partly, and a handle screwing into the aperture of the holder.

LEOPOLD HERRMAN.
